UNITED STATES PATENT OFFICE.

MERVYN W. PALMER, OF NEW YORK, N. Y., ASSIGNOR TO PARAMOUNT FAMOUS LASKY CORPORATION, OF NEW YORK, N. Y., A CORPORATION OF NEW YORK.

CONTROL MECHANISM.

Application filed January 4, 1927. Serial No. 159,010.

My invention broadly relates to automatic electric control devices and has for one of its objects the provision of automatically operating controlling mechanism whereby 5 the voltage in a line may be maintained within very close limits, or, stating it in another way, automatically operating controlling mechanism governed by the resistance in the circuit being controlled and arranged 10 so as to maintain the resistance in the line within certain predetermined limits.

While my improved apparatus is capable of numerous applications such as electric furnace installations, automatic electric elevator operation, search-lights, arc-lights for medical uses, projection machines and spot-lights, it will, for the sake of clarity, be described with specific reference to spot-lights.

In a spot-light, as is well known, current 20 is passed between spaced electrodes, and in the carbon arc, that is to say arcs employing carbon electrodes, the carbon itself is the source of light, while in the high intensity arc the carbon acts as a holder for the real 25 source of light, which is a small body of luminous gas. In both types of arc, however, it is necessary to effect a periodic adjustment of the electrodes in order that the arc voltage may be maintained within predetermined 30 limits, or, stating it another way, the resistance across the electrodes must be maintained substantially constant, for best results.

With the spot-lights employed in moving 35 picture studio and theatre work, it is customary to adjust the electrodes by hand, the adjustment being made at the will of an operator whose judgment must be relied upon. In studio work where a great many 40 spot-lights may be in use at the one time, it is customary to employ one operator for each machine, which of course imposes a heavy operating expense upon each machine, and inasmuch as the human element in such 45 cases must be relied upon, results are not always what may be desired.

To avoid the annoyance and expense incident to the old method as just outlined of effecting the proper adjustment of the arc, 50 I provide means applicable to carbon arcs as well as high intensity arcs wholly automatic in its operation and controlled by the arc voltage whereby a variation in this volt-

age beyond certain prescribed limits will effect a restoration of the electrodes to a predetermined relation and re-establishment of the proper arc voltage. 55

More specifically my invention contemplates the provision of a reversible electric motor mechanically and electrically connected to the electrodes to be controlled, whereby upon an increase or decrease in the arc voltage the motor will be energized to effect rotation of the same in the proper direction to in turn move the electrodes in the proper direction to restore or re-establish normal operating conditions. 60 65

In the accompanying drawing illustrating the application of my invention to a spot-light of the carbon arc type, as well as high 70 intensity arcs,

Fig. 1 is a wiring diagram of my invention;

Fig. 2 is a part sectional elevational view 75 of the apparatus which may be employed in the commercial use of the invention;

Fig. 3 is a section through Fig. 2 taken on the line 3—3 thereof;

Fig. 4 is a section through Fig. 2 taken on the line 4—4; 80

Fig. 5 shows my invention applied to a high intensity arc;

Fig. 6 is a section on the line 6—6 of Fig. 5;

Fig. 7 is a wiring diagram modified as 85 to the diagram of Fig. 1; and

Fig. 8 is a wiring diagram of a still further modification.

Referring to the drawings in detail and first of all to Figs. 2, 3 and 4, 1 designates 90 a lamphouse which may be of usual construction. Mounted within the lamphouse on suitable guides 2 is a carriage 3 carrying the electrodes 4 and 5. The electrode 4 is carried in a holder 6 and the electrode 5 in 95 a holder 7, the holders 6 and 7 in turn being threaded upon a rod 8 mounted for rotation but held against longitudinal movement in the carriage 3. The threaded portion 9 of the rod 8 which receives the holder 10 6 is threaded oppositely to the portion 10 carrying the holder 7, so that rotation of the rod 8 will effect movement of the holders in opposed directions.

Mounted on the under side of the lamp- 105 house is a platform, shelf or other suit-

able support 11 for a reversible electric motor 12, the armature shaft of which is designated 13.

The armature shaft 13 carries a worm 14 meshing with a worm wheel 15, carried on a stub shaft 16. The shaft 16 is connected by a universal joint 17 to a stub shaft or rod 18 having telescopic connection to a rod 19 connected by a universal joint 20 to the threaded rod 8 carrying the electrodes.

The worm wheel 15 is free on the shaft 16, but a driving connection is normally maintained between these two members by a clutch. This clutch is illustrated in Fig. 4, and from this figure it will be seen that the lower side of the worm wheel 15 is provided with a clutch face 21 co-operating with a clutch sleeve 22, the latter being keyed as indicated at 23 to the shaft 16. The sleeve 22 is normally held in clutching or driving position by a spring 24. When it is desired to release the clutch so that the shaft 16 may be turned by hand without rotating the motor 12, the clutch sleeve 25 may be pulled downwardly by means of the knob 25 provided for that purpose and by holding the sleeve in this position and rotating the knob the shaft 16 may be turned to adjust the electrodes.

30 The jointed connections above described and the clutch mechanism just referred to provide a drive from the motor 12, to the rod 8, and rotation of this rod will, it is obvious, adjust the electrodes 4 and 5 relatively and in a direction depending upon the direction of rotation of the motor.

In operation of the spot-light it is desirable to adjust the electrodes longitudinally of the lamphouse, that is, to vary the distance between the electrodes and the lens 26. This adjustment is effected by sliding the carriage 3 along the guides 2, by means of a rod 27 provided for that purpose; this adjustment being effected without disturbing the drive between the motor 12 and rod 8, due to the universal joints above described, while the telescopic connection between the rods 18 and 19 permits of this adjustment without varying the position of the arc vertically.

Referring to the wiring diagram of Fig. 1, it will be seen that the armature 28 of the motor 12 is connected across two branch circuits designated 29 and 30, the circuit 55 29 being provided with fixed resistance 31 while the circuit 30 is provided with variable resistance 32. The electrodes 4 and 5 of the arc are in the branch circuit 29. The field of the motor is designated 33 and as illustrated is connected across the electrodes 4 and 5.

The operation of my improved control mechanism so far as its electrical features are concerned and so far as its automatic operation is concerned is as follows, assum-

ing that the electrodes 4 and 5 are in contact with each other and that current is flowing through the branch circuits 29 and 30. Owing to the arrangement of the resistances 31 and 32, there will be a difference in potential across the terminals of the motor 12 to cause the armature 28 thereof to be energized and hence the motor to be rotated. The rotating of this armature 28 through the mechanism described in connection with Figs. 2, 3 and 4 will cause the rod 8 to rotate in the proper direction to effect a separation of the electrodes 4 and 5. When these electrodes have separated a predetermined distance, the increase in resistance, due to the separation of the electrodes 4 and 5, will establish a balance between the branch circuits 29 and 30. In other words, there will be no difference in potential at the terminals of the motor 12 with the result that the motor armature 28 will come to rest. As soon as the electrodes 4 and 5, or rather the positive electrode 4, has burned away or disintegrated due to the arc across these electrodes sufficiently to, so to speak, upset the balance between the branch circuits 29 and 30, a difference in potential across the terminals of the motor 12 will again occur, with the result that the armature will be rotated, but this time in the opposite direction, so as to move the electrodes 4 and 5 toward each other until a balance has been reached again. Consequently, it will be seen that no hand manipulation of the electrodes 4 and 5 is necessary in order to maintain the voltage across the electrodes 4 and 5 within predetermined limits, with the result that the spotlight will be operated at a substantially constant voltage.

It will be understood that the variable resistance 32 is only necessary for the initial setting of the device, no manipulation of this resistance being necessary after the device has once been adjusted, the entire operation of my improved apparatus being automatic.

It will be understood also that if the switch (not shown) controlling the supplying of power to the electrodes 4 and 5 be opened when the electrodes are out of contact, a closing of this switch will cause current to flow through the motor 12 in a direction to cause the motor to move the electrodes 4 and 5 toward each other. Inasmuch as under these conditions the arc has not been "struck", it will be obvious that the motor will continue to so rotate until the electrodes engage each other or make contact. When the electrodes contact, the motor will reverse in direction, separating the electrodes 4 and 5, to "strike" an arc and will continue to rotate in a direction to separate the electrodes until the latter have been separated the correct distance as determined by the initial setting of the

machine. Thereafter conditions, so far as operation is concerned, are as has been described above.

As I have mentioned above, a spot-light 5 has been illustrated and described in detail for illustrative purposes only, inasmuch as my invention has many applications, some of which have been enumerated above. For example, I have mentioned an electric furnace as one possible application of my invention, and it will be obvious to those skilled in this art that in such a case my invention may be employed to control the resistance and hence the voltage of the electric 10 circuit of the furnace by inserting in this circuit a pair of contacts in which the contact pressure may be controlled by the motor 12. In other words, in such a case it is merely necessary to substitute such contacts for the electrodes 4 and 5 shown in Fig. 1, the resistance of the circuit instead of varying with the change in distance between the electrodes 4 and 5, varying with or being varied by the pressure of the two 15 contacts upon each other.

As above pointed out, my invention is adapted for application to high intensity arcs, and such an application has been illustrated in Figs. 5 and 6.

Referring to these two figures of the drawing, 34 and 35 designate, respectively, the positive and negative electrodes of a high intensity arc. The positive electrode 34 is rotated continuously as is customary through 20 the medium of an electric motor. In the present case, this motor is designated 36 and corresponds to the motor 12 of the embodiment of my invention already described. Also, as is customary, the positive electrode 34 is fed forward, that is to say, in a direction toward the negative electrode 35. The negative electrode 35, as distinguished from the positive electrode, is stationary so far as rotation is concerned but is adapted to be 25 adjusted relatively to the positive electrode 34 by the electric motor 36, as will be described presently in detail. In other words, as applied to high intensity arcs, my invention provides means for maintaining the proper arc voltage at all times as in the 30 case of the carbon arc already described.

The positive electrode 34 is mounted on a suitable stand 37 to which is secured a bracket or other support 38 carrying the electric motor 36. The negative electrode 35 is mounted in a suitable head 39 supported by an arm 40 carried by the member 37. This part of the apparatus is conventional and will not be described in any great detail for this reason.

The armature shaft of the motor 36 is designated 41 and is provided with a worm 42 shown clearly in Fig. 6, this worm meshing with a worm wheel 43, the latter being 45 mounted on a sleeve 44 which surrounds a

vertically extending shaft 45, the sleeve being clutched under ordinary conditions to the worm wheel 43 by teeth 46. The shaft 45 carries a gear 47 rigidly secured to the shaft and meshing with a gear 48 carried 50 on a short shaft 49 shown in Fig. 6. The upper end of this shaft is provided with a bevelled gear 50 meshing with a bevelled gear 51 which in turn meshes with a bevelled gear 52 carried at the lower end of a 55 flexible or jointed shaft 53. This shaft is provided with a universal joint 54 and has a telescopic connection with a shaft 55 which in turn is provided with a universal joint 56 and is connected by this universal joint 60 to a shaft 57 provided with worms 58 and 59, these worms meshing with worm gears 60 and 61, respectively, actuation of these worm gears effecting movement of the negative electrode 45 longitudinally. We have, 65 therefore, a driving connection from the motor 36, that is to say, from the armature shaft 41, to the negative electrode 35 whereby rotation of the motor will effect adjustment of the electrode. The drive for the 70 positive electrode 34 which, as above noted, is constantly rotated and fed forward intermittently, comprises a gear 62 on the upper end of the shaft 45 meshing with bevelled gear 63 on the end of a drive shaft 64. The 75 opposite end of this drive shaft is provided with a gear 65 meshing with a bevelled gear 66, the latter driving a bevelled gear 67 on the lower end of a shaft 68. This shaft is connected by a universal joint 69 to a shaft 100 70, the latter being connected by a universal joint 71 to a shaft 72 on the upper end of which is a bevelled gear 73 meshing with a gear 74 connected to the positive electrode 34 so that rotation of the gear 74 through 105 the gear train just described by means of the motor 36 will cause the positive electrode 34 to be rotated. The feed for the electrode 34 is the conventional form and hence will not be described in detail.

The operation of this device is similar to that described in connection with the carbon arc illustrated in Fig. 2, the wiring diagram for the motor 36 being arranged the same as shown in Fig. 1. In other words, assuming that the switch (not shown) supplying current to the motor 36 is opened when the electrodes 34 and 35 are in the position shown in Fig. 5, closure of this switch will effect rotation of the motor in 110 a direction to feed the electrodes, particularly the electrode 35, in a direction to bring these two electrodes in contact, whereupon, due to the drop in resistance on account of the contact of the two electrodes, the motor 115 will be reversed automatically, the arc will be "struck" and the electrodes will continue to separate until a balanced condition electrically is established, whereupon the motor 120 36 will come to rest. In other words, as 125 130

pointed out above, the operation of this device is the same as that of the carbon arc of Fig. 2.

In case adjustment is desired of the electrodes independently of the motor 36, the sleeve 44 is pushed upwardly against the action of the spring 75 so as to disengage the teeth 46 from the face of the worm gear 43. This sleeve is keyed or otherwise rigidly secured to the shaft 45 and the shaft may be rotated so as to cause the electrodes to be adjusted.

The wiring diagram of Fig. 7 is a modification of the diagram of Fig. 1. Referring to this figure of the drawing, the motor 12, the position of which corresponds to the motor 12 of Fig. 1, is an alternating current motor and has its rotor short-circuited. This motor is provided with two field windings 76 and 77 of different resistances, each field when energized alone producing rotation of the motor in a different direction. It will be obvious from an inspection of this diagram that one or the other of these field windings will be energized when an unbalanced condition exists in the circuit due to improper spacing of the electrodes 4 and 5, and depending upon which field is energized, the motor will be caused to rotate in a corresponding direction, thereby actuating the electrodes 4 and 5 in a direction to restore balanced conditions again.

While the two specific embodiments of my invention as above described are suitable for certain classes of arcs, that is to say, arc lights used for certain classes of work, it may be desirable or necessary in some instances to use a larger motor than I have found necessary to use in the forms illustrated. In such event I propose to employ two motors, one of which may be a very powerful motor, relatively speaking, and adapted to actuate the necessary mechanism for effecting the desired electrical conditions. The other motor in this embodiment of my invention may be termed a pilot or control motor, and as it will have practically no work to do except the mere opening and closing of a switch, this pilot or control motor may be of very low capacity, the throwing of the switch by the pilot motor controlling the circuit of the heavy motor to cause the same to operate. Inasmuch as the particular switch mechanism and other mechanical features of this embodiment of my invention are of minor importance, I have deemed it sufficient to merely illustrate this feature of my invention by way of a diagram, which is the diagram of Fig. 8.

Referring to the wiring diagram of Fig. 8, it will be seen that the electric motor 12, which is provided with two field windings 76 and 77, respectively, is mechanically connected to a reversing switch 78, this revers-

ing switch controlling the circuit to a reversible electric motor 79. This motor, as above pointed out, may be of any necessary size but is intended for heavy duty, and it is to be understood will be mechanically connected to the device or devices to be controlled, such as the electrodes 4 and 5, which have been illustrated in this diagram merely for clarity of description and illustration. The reversing switch 78 is adapted to make contact with either contact 80 or 81, as the case may be, depending upon conditions across the electrodes or other devices being controlled. In short, this diagram is intended to illustrate an application of my invention to an installation wherein the devices 4 and 5, which are to be controlled, are adapted to be actuated by the reversible motor 79, and as above pointed out, inasmuch as the devices represented by the electrodes 4 and 5 might be of such a nature as to require a heavy-duty motor for their actuation, I have provided the heavy-duty motor 79, which is controlled by the relatively light-duty motor 12. The only work to be performed by the motor 12, as will be apparent, is actuation of the reversing switch 78. Here, then, I have provided an apparatus wherein the direction of rotation of the motor 12 is controlled by the resistance across the members 4 and 5, the direction of rotation of the pilot or control motor 12 in turn controlling the direction of rotation of the heavy-duty motor 79, the latter, as will be apparent, to control the relative position of the members 4 and 5 so that the voltage across these two members may be maintained within predetermined limits.

From the foregoing it will be seen that I have provided means for maintaining the voltage in a line within close limits, and while my invention is capable of many applications, I have illustrated and described the same in connection with a carbon arc spot-light and in connection with a high intensity arc. It will be seen also that I have provided several embodiments of my invention, so far as the electrical side thereof is concerned, the diagram of Fig. 1 showing a motor with but one field winding but with the armature winding so arranged that the direction of rotation of the motor is selected by the resistance across the electrodes 4 and 5. In other words, speaking now of a carbon arc spot-light, when the electrodes are burned away so that the resistance across the electrodes is increased to a point where there is a voltage drop across the electrodes beyond a predetermined degree, the electrodes will be automatically brought closer together. This arrangement also provides for the initial "striking" of the arc, the motor 12 operating automatically to bring the electrodes 4 and 5 into contact with each other,

whereby the resistance across these electrodes is sufficiently reduced to cause the motor 12 to be reversed, separating the electrodes to strike the arc and continuing this separation of the electrodes until the voltage across the same is brought within the predetermined limit.

It will be seen also that in Fig. 7 I have varied this arrangement, in that the motor is provided with two field windings, the excitation of one field causing the motor to rotate in one direction, while the excitation of the other field causes the motor to rotate in the opposite direction, the excitation of these fields being selected by the resistances across the electrodes 4 and 5. In other words, this embodiment of the invention will operate to maintain the voltage across the electrodes 4 and 5 within the predetermined limits, as in the case of the diagram of Fig. 1.

It will be seen also that in Fig. 8 I am able to obtain the same results electrically and mechanically, and while in this figure I have modified the wiring diagram of Fig. 7, in that I have added the motor 79 thereto (the motor 12 merely controlling the circuit to this motor), it is to be understood that the motor 79 could be added to the diagram of Fig. 1, if desired.

The armature and field connections in the diagram of Fig. 1 obviously may be interchanged, if desired.

It will be obvious that many changes may be made in the construction illustrated in the accompanying drawing as above described, without departing from the spirit of the invention, and accordingly my invention is not to be limited to the precise form here shown and described.

What I claim is:

1. In combination, a pair of co-operating electrodes, two branch circuits, said electrodes being in series with one of said circuits, a reversible electric motor having its

armature connected across said branch circuits, a field for said motor connected across said electrodes, and means for mechanically connecting said electrodes to said motor, whereby a variation in the voltage of the current flowing in the circuit containing the electrodes will effect rotation of the motor armature to actuate the electrodes and restore the voltage to normal.

2. In combination, two branch electric circuits, an arc light structure comprising two electrodes inserted in series with one of said branch circuits, an electric motor mechanically connected to said electrodes for effecting relative adjustment thereof, said motor comprising an armature connected across said branch circuits and a field connected across said electrodes, whereby the voltage across said electrodes will be maintained within predetermined limits.

3. In combination, two branch circuits, an arc light comprising a pair of electrodes inserted in one of said circuits, an electric motor comprising an armature mechanically connected to said electrodes and adjustably connected across said branch circuits for determining the operating position of the electrodes, and a field for said motor connected across said electrodes.

4. In combination, a pair of branch circuits, an arc light comprising two electrodes inserted in series with one of said circuits, an electric motor mechanically connected to said electrodes for adjusting the same automatically, the armature of said motor being adjustably connected across said branch circuits for determining the operating position of the electrodes, and the field for said motor being connected across said electrodes.

This specification signed this 3rd day of January, 1927.

MERVYN W. PALMER.
